United States Patent Office.

WILLIAM DUNN, OF NEWARK, NEW JERSEY.

Letters Patent No. 69,827, dated October 1, 1867.

IMPROVED ADJUSTABLE FRAME FOR STRETCHING HIDES.

The Schedule referred to in these Letters Patent and making part of the same.

Be it known that I, WILLIAM DUNN, of the city of Newark, in the county of Essex, and State of New Jersey, have invented a new and useful machine for stretching hides which I call "An Improved Adjustable Frame for Stretching Hides," of which the following is a full, clear, and exact description, reference being had to the annexed drawings, making part of this specification, of which—

Figure 1 is a side view, and

Figure 2 an end view.

Fig. 1. A A is a stationary frame, on the top or back of which the hide is thrown. B B, movable planks or "toggles," to which the edges of hides are tacked on each side of the frame. These planks work independently of each other, and each in one continuous piece, or divided in the centre and connected by a hinge, C. D D are levers, and E chains or loops, by which the planks B B are drawn down, and the hide stretched when drawn down by the levers. F F are iron racks and stops, by which the planks B B are held in place. f g are chain and hooks, which by the application of the lever D at this point draw down and secure in position the middle of planks B B, thus stretching the belly of the hide, which is the part susceptible of the greatest extension, to its utmost capacity without danger of bursting the other parts by too great a strain.

Fig. 2. A A is an end view of the stationary frame. B B, ends of movable planks or "toggles." F F, iron racks and stops, by which the planks B B are held to places when drawn down by the lever G. G is the hide, which is laid over the top or back of the stationary frame A A, and is tacked to the movable planks or "toggles" B B at bottom and ends. The dotted lines h h, in fig. 1, show the positions of the movable planks or "toggles" when the hide is first tacked on; the dotted lines I I show their position when the hide is stretched. The "toggles" on the ends of the stationary frame A A are worked by the application of the lever, as shown on the drawing, and when drawn out are held in position by wedges set in between the back of the "toggle" and the upright of the stationary frame.

The main object of the machine is to stretch hides which are to be enamelled for carriage-tops, &c. The hide is tanned and wet when put on the frame to be stretched and left to dry. Now the nature of a hide is such that while some parts swell, (as the belly and flanks,) and are susceptible of a great deal of stretch, other parts, (such as the back and shoulders,) are susceptible of very little stretch, and hence the necessity of a machine which will graduate itself to some extent, at least, to such parts in proportion to its stretching power. The great difficulty in stretching hides is their liability to burst or tear in some places before the other parts are properly stretched, and this is sure to occur where the power is applied equally, or in one line, or with one motion, so that in those cases the hide has to be left but partially stretched in some places, and when put on the enamelling-frame those places will not be level but will pucker up, to the great annoyance of the workmen and detriment of the work. By examining the drawing which accompanies these specifications, it will be observed that one side of the hide can be stretched more than the other if necessary, as is often the case, for the workmen seldom place the hide accurately square on the frame, nor is the hide ever exactly equal on both sides of the backbone. The movable planks or "toggles" working independently of each other, one side of the hide can be stretched six, eight, or ten inches, and the other, one, two, or three inches, or not at all; or one end of each side can be stretched and the other not at all, or the centres can be stretched without the ends, and, in a word, by this invention the hide can be stretched in any way required with entire safety, and without danger of bursting or tearing.

I claim that my invention effectually overcomes these objections, and stretches the hide to its fullest extent in every part, and an experience of over thirty years in the leather business gives me reason to think that I judge correctly.

What I claim as my invention, and desire to secure by Letters Patent, is—

The application of movable planks to a stationary frame in the manner set forth, and worked by levers as shown, the planks divided in the middle and connected by a hinge, or each plank in one continuous piece, and working independently of each other, thus adjusting itself to the formation of the hide, and stretching each part to its fullest capacity.

WILLIAM DUNN.
